LUBRICATING INSTALLATION

Joseph Bijur, New York, N. Y., assignor to Auto Research Corporation, a corporation of Delaware

Application December 27, 1929, Serial No. 416,787

57 Claims. (Cl. 184—7)

My present invention is concerned with automatic lubricating systems of the character in which oil from a central source is delivered under pressure through a series of distributing conduits to the various bearings of a machine during running of the latter. The invention is especially concerned with a system adapted to meet the peculiar requirements of chassis lubrication.

An object of the invention is to provide a chassis lubricating system to function automatically as long as the engine is in operative condition and without any attention whatsoever, not even the manipulation of a valve or handle or any adjusting or other manual operation, in order to initiate or maintain operativeness.

Another object is to provide a simple, inexpensive fully automatic system of the above type which requires no special reservoir for chassis oil but utilizes engine oil derived from the crankcase.

Another object is to provide a system of the above type, proof against leakage or drip while the car is parked, yet at all times, when the car is running, delivering oil at substantially constant rate to the individual bearings in unvarying proportions, in accordance with their needs, adequate delivery being assured under all operating conditions and without danger of under-oiling or overoiling, regardless of varying road conditions or variations in oil viscosity, incident to the difference between summer and winter temperatures.

Another object is to provide a system of the above character, which will function reliably, with oil from the crankcase, despite the use of diminutive pump mechanism and flow controlling fittings having highly restricted flow passageways therein, that are inherently subject to clogging by solid particles in the oil.

Another object is to supply the chassis lubricating pump with oil from the usual engine oil filter, yet to assure a supply of clean oil from the crankcase to the chassis system even should the engine oil filter become clogged.

Another object is to provide a system which affords a ready visual indication of the condition, and incidentally, of the level of the oil which is being used, and gives the driver unmistakable notice when a fresh supply of oil is required in the crankcase.

Another object of the invention is to provide a self-contained motor and pumping unit utilizing vibratory or other energy as the motive means for the pump and capable of ready insertion into the crankcase of the engine.

In a preferred embodiment, the system com-

prises a chassis oil pump distinct from the engine oil pump, but deriving its charge from the engine oil pan and preferably submerged in the latter, said chassis oil pump automatically and continuously operated throughout running of the vehicle and connected to a chassis distributing line equipped at the various chassis bearings with flow controlling outlets, preferably of the drip plug type. The pump is preferably a reciprocating one actuated by suitable motive means. Where the inertia of an appropriate vibratory weight is utilized as the motive means for the pump the latter would be of minute volume. Air trapped in the gauge line helps to level out the pump strokes especially where a pump of larger volume and lesser frequency of operation is utilized.

Preferably the usual engine oil filter delivers to a well within the oil pan in which the chassis lubricating pump is submerged, and auxiliary filter means in the wall of the well assures the entry of a supply of clean oil from the crankcase for the chassis lubricating system even if the engine oil filter should become clogged.

Another feature resides in indicating means which at all times shows whether the oil in the crankcase is of proper quality for continued use as an engine and chassis lubricant. The chassis lubricating system used being of constant feed rate, regardless of the thickness or viscosity of the oil in the chassis lines, the application of a flow resistance in the course of flow, does not interfere with the reliability of chassis lubrication. Oil being fed through such resistance at the nearly constant rate determined by the pump and being maintained during its flow through the resistance, at the nearly constant temperatures of the oil pan or the water jacket, the difference in pressure potential across the terminals of said resistance is a measure of the viscosity of the oil at said constant temperature. Accordingly, a suitable pressure gauge connected across the terminals of such resistance affords the desired reading, either quantitatively in units of viscosity, or qualitatively in terms of oil suitability.

The invention may be more fully understood from the following description in connection with the accompanying drawings, wherein:

Fig. 1 is a fragmentary perspective view showing the forward portion of a chassis and indicating diagrammatically the location of the various elements of my improved centralized lubricating system.

Fig. 2 is a greatly enlarged fragmentary transverse sectional view through the crank case and

through the removable self-contained pump, motor, filter and resistor unit which is disposed within the crank case.

Fig. 3 is a further enlarged vertical sectional detail through the lower end of this unit,

Figs. 4 and 5 are transverse sectional views on the lines 4—4 and 5—5 respectively, of Fig. 3.

Fig. 6 is a diagrammatic view taken from the exterior of the crank case and showing the connections between the gauge and the system.

Fig. 7 is a sectional plan view on the line 1—1 of Fig. 6.

Fig. 8 is a face view of the gauge with parts broken away and in section for clearness.

Fig. 9 is a vertical sectional view on the line 9—9 of Fig. 8.

Fig. 10 is a view, somewhat similar to Fig. 2 but illustrating a modified arrangement in which the resistor unit is mounted in the water jacket, the motor and pump unit being shown mainly in elevation.

Fig. 11 is a view taken exteriorly of the crank case showing diagrammatically the system of Fig. 10 and the various connections to the resistor, the gauge, and the distributing conduit line,

Fig. 12 is a plan view of the top of the pump and motor unit taken approximately on the line 12—12 of Fig. 11.

Fig. 13 is an enlarged sectional detail of the resistor element which is used in the water jacket, and,

Fig. 14 is an enlarged longitudinal sectional view through one of the flow controlling drip plug fittings which are common to both systems.

In Fig. 1 of the drawings 10 designates the usual chassis frame, mounting an engine 11 with in the engine compartment cooperatively defined by the radiator 12, hood 13, and dashboard 15.

A minute capacity force pump P shown in detail in Figs. 2 to 5, withdraws oil from the bottom of the engine crank case 16 and, while the car is in motion, feeds it continuously into a distributing system delivering oil at the various chassis bearings. The force pump is operated by an inertia motor M, the details of which are shown in Fig. 2, this motor deriving energy from vehicle vibration.

The oil distributing system preferably consists of a connected series of small bore liquid-filled conduits such for instance as the main 17 leading from the pump and into the conduit 18 which follows along one of the channel frames and has various branch conduits such as 19 leading to the individual chassis bearings.

The outlets from the distributing system preferably comprise flow controlling fittings such as 20, an illustrative embodiment of which is shown in detail in Fig. 14 and will now be described. The fitting body 21 has a threaded end 22 for application to a threaded socket in the fixed part of a bearing, and is provided with sockets 23 and 24 at its respective ends connected by a longitudinal bore 25 substantially filled by a flow restriction pin 26. The branch conduit 19 which supplies this drip plug is attached thereto by a pressure-tight coupling, designated generally at 28. Oil flowing into the drip plug from the pipe 19 passes through a wad of filter material 29, disposed within the socket 24 and encased within a wire mesh basket 30 which prevents disintegration of the filter material. This filter effectively guards the minute crevice around the restriction pin 26 from becoming fouled or clogged with scale or chips which may be carried from the interior of the small bore tubing 19 by the flowing oil stream.

Within the socket 23 there is mounted a light, soft faced valve 31 sustained against loss by a retaining collar 32 force fitted into the mouth of the socket and adapted, when suction conditions exist within the pipe 19, to be drawn against an outwardly facing seat 33.

As in my prior Patent No. 1,632,772, the bores 25 of all of the drip plugs may be uniform and the pins 26 are made in various sizes so that the proportional rate of flow through the various drip plugs of the system may be readily predetermined by the selection of plugs having pins of correct size. The restriction of the drip plugs affording high resistance to flow, they sustain pressure, which accordingly is nearly uniform throughout 15 the liquid filled distributing system.

The purpose of the light valve in the present invention is similar to that of my prior Patent #1,732,212 of October 15, 1929, that is, to prevent siphoning between drip plugs at different levels, 20 at times when the vehicle is not in motion and the various pipes of the system are filled with oil.

In the embodiment of Fig. 2, but slight changes have been made in the conventional crank case structure, in order to accommodate the motor and pump unit. Set inwardly from one side wall of the oil pan is a vertical partition 34 cooperating with the wall of the oil pan 16, to define an oil well 35. The terminal end of the return pipe 36 from the usual engine oil cleaner (not shown) 30 spills oil into the well 35, partition 34 tending to segregate this oil from the dirtier oil in the remainder of the oil pan.

As indicated by legends and dotted lines in the drawings the high oil level in the crank case 35 is just below the top of the partition 34. A filter 38 secured to wall 34 and covering a corresponding opening 37 in said wall, affords a path for the admission of clean oil from the crank case to well 35. A supply of clean oil to the 40 chassis lubricating system would thus be assured, even though the engine oil filter that usually affords the supply through pipe 36 should become clogged.

The only other change which, in some engines, represents a slight departure from standard structure is the provision of laterally offset pockets 40 and 40^a in the crank case and oil pan walls the top of the pocket constituting a horizontal platform portion 39 interrupting the 50 usual curve of the crank case 15. A circular opening 41 in the platform is vertically aligned with the well 35 and my improved motor M and pump P, preassembled as a unit within an elongated tubular casing 42, are dropped through 55 opening 41 and secured in position as will be later described, so that the pump P is immersed in the oil in the well 35. The shell 42 not only constitutes the casing of the self-contained pump and motor unit but additionally carries a 60 filter assemblage indicated generally at F which filters the oil supply passing from the well into the pump.

The cylinder 42 of the self-contained motor, pump and filter unit is encircled near its upper 65 end by a collar 44 soldered or otherwise connected thereto. The flat bottom of this collar seats on the platform 39 and is bolted or otherwise secured thereto as at 45. When thus applied, the lower end of the cylinder extends near 70 ly to the bottom of the well 35 as shown.

The intermediate portion of the cylinder 42 is internally reinforced by a cylindrical sleeve member 46 on to opposite ends of which are force fitted oppositely facing cup-like partition 75

disks 47 and 48. These disks are formed with marginal flanges 49 to abut the ends of the sleeve 46; each disk is apertured at 50 and each disk is provided with a central down-struck sleeve or collar portion 51 serving to provide strong and substantial slide bearings for the vertical reciprocating connecting rod 52 which directly connects the massive inertia weight 53 of the motor with the minute plunger 54 of the pump.

Referring more specifically to the pump mechanism, a circular horizontal block 55 is mounted in the slightly enlarged lower end 42a of the cylinder 42 and is held in position by a radial pin 56. The pump body 57 at its lower end is formed with a head 58 which limits the insertion of the shank 57 into a central opening 55' in the block into which it is press-fitted. The pump body projects upwardly above the block 55 and is formed with a longitudinal bore 59 intersected above the block by a transverse bore 60 and terminating at its lower end in a downwardly facing socket 61, the lower end of which is closed by a plug 62. The passageway 60 provides a pair of inlet ports for the pump. That portion of the bore 59 between the inlet ports and the socket 61 constitutes the pump cylinder proper and the portion of the bore 59 above the port 60 serves simply as a guide for the reciprocating pump plunger 54.

In Fig. 3 the plunger 54 is shown in its normal position of rest approximately at the inlet ports 60 but leaving sufficient clearance for gravity flow of oil which may have accumulated above the block 55 into the working chamber 59a of the pump. Outflow from this chamber is normally checked by a soft faced valve 63 urged upwardly by a coiled expansion spring 64 against a downwardly facing seat 65 in the socket 61. This spring reacts against a cup 66, force fitted into the socket 61 and the lower enlarged end of the socket is closed by the plug 62 which has a screw driver slot 67. Oil forced past the valve 63 escapes from the socket 61 through a radial port 68 delivering into a radial passageway 69 in the block 55. The oil is thence fed through a member R, not essential to the operation of the system and hereinafter described, and is delivered to the chassis lubricating system by way of pipe 107 which extends upward along cylinder 42 and delivers through outlet 108 to the chassis line 17.

The filter assemblage, designated generally at F, includes a relatively dense filter pad of large area cooperatively formed of a series of stacked felt filter disks 72, internally reinforced by a wire basket 73, having a flange 74 spun over upon the top of the disks to confine them against endwise displacement. A pressed metal plate 75, secured in the bottom of the cylinder section 42a by a split ring 76, is provided with openings 77 through which oil from the well flows upwardly into the annular space between the cylindrical filter pad 72 and the cylinder wall 42a. The bottom of the basket 73 is formed with an opening 78 therein, encircled by a reinforcing ring 79 and the center of the plate 75 is pressed upwardly through the opening 78 and expanded over the disk 79 as indicated at 80 thereby locking the plate 75 and the filter disks and basket liner together. The filter washers 71 are held under light compression by an annular rib 81 extending downwardly from the block 55 and biting into the top of the stack and an annular rib

82 pressed upwardly from the plate 75 digs into the bottom of the stack.

The oil flows freely into the annular space around the cylindrical filter and seeps slowly by gravity into the basket, thence rising through a vertical passageway 83 in the block 55 and filling the chamber 71 above the block to approximately the same level as the level in the well 35.

The inertia motor which actuates the pump 10 comprises a weight 53 fixed by a compression coupling 84 to the upper end of the connecting rod 52 and is sustained in free floating position by a coiled expansion spring 85 bottoming upon a plate 86 fitting into the bottom of the cup-shaped partition disk 48. The upper end of the weight 53 is cylindrical in form nearly filling the cylinder 42. In fact, due to the rigid connecting rod, bearings 51, the clearance between the cylinder and the weight may be sufficiently small to permit a substantial air checking effect on the weight, yet the weight will not rattle against the adjacent cylinder walls even when the cylinder 42 is laid on its side for purposes of shipping.

The lower end of the weight is conically tapered 25 at 87, cooperating with the upper portion to define a downwardly facing shoulder 88 which rests upon the spring 85. The lower tapered end of the weight fits within the spring 85 and is adapted upon violent down strokes to contact 30 with a coiled buffer spring 89 centered within a flange 90 on the plate 86 and reacting against the partition disk 48. While the specific pump and motor construction is desirable, the generally similar assembly shown in the copending application 35 Ser. No. 389,839 filed October 11, 1929 may be used to advantage.

During normal running of the automobile, the vibration incidental to operation even on smooth roads will cause the weight 53 to reciprocate and the plunger 54 to force successive small charges of oil beyond the outlet valve 63 into the distributing system. Violent up-swings of the weight involve no increased rate of feed, since the pump plunger is then simply withdrawn further than necessary but the effective pump stroke is no longer. Violent down-strokes of the weight are effectively checked by the buffer spring 89. Thus, under all running conditions, a substantially uniform flow or constant volume of oil will 50 be delivered by the pump. The pressure available at the pump, by reason of the small diameter of its piston, is sufficient to insure constant volume delivery into the system, regardless of whether the oil in the distributing conduit system 55 be quite fluid in summer or highly viscous in winter. Filtered oil that has seeped through pad 72 will stand in the chamber 71 and immerse pump P, the working chamber 59a of which is filled through the ports 60. The valve 63, being normally seated, prevents venting of the body of oil standing in the various pipes of the distributing system. The drip plug valves 31 check any siphoning tendency between drip plug outlets at different levels. Thus, when the car is standing 65 still, no oil will escape from the system.

In operation, while the car is in motion the inertia motor M will reciprocate, weight 53 being balanced with sufficient delicacy by the spring 85 to insure a sufficient amplitude of vibration to operate the force pump P even when the car is travelling over smooth roads thereby expelling a rapidly repeated series of minute oil charges into the distributing system. The flow resistance of the 75

distributing conduits is so small as compared with the flow resistance of the drip plugs that pressure loss between the pump and the outlet of the system is a negligible factor in the operation of the system, the various drip plug fittings passing such proportions of the total feed as correspond to the respective ratings of said drip plugs, to lubricate the various bearings in accordance with the requirements thereof.

The use of comparatively dirty crank case oil is made possible for chassis lubrication by the very effective filter system which is employed. Substantially all of the oil which enters the well 35 comes either directly through the pipe 36 from the engine oil cleaner or filter or through the filter pad 38. If foreign particles should reach the well, for instance, by the splash of dirty oil from the crank case, they will in part settle to the bottom of the well and in part be filtered out by the pad 72 before they can reach the relatively delicate mechanism of the force pump. The flow restrictions, of the drip plugs are independently guarded by strainers 29 which serve to entrap any chips entrained from the metal walls of the flow passages.

The motor and pump unit is compact and may be readily installed and as readily removed for purposes of inspection or repair. The pump, motor and filter constitute a unitary assembly which may be simply dropped through the opening 41 and held in place by bolting down the collar 44.

The various pipes which lead from this unit, such for instance, as the pipes 110, 111, and 17 may be conveniently coupled, as shown, to associated conduits at the suspension collar of the motor and pump unit.

The apparatus is so designed that no adjustment thereof in use is necessary, since neither changing weather conditions nor changing oil conditions, nor changing conditions of the road over which the car travels nor of the speed at which the car is travelling can bring about improper lubrication. The pump feeds substantially constant volume and thus functions at all speeds and on all types of roads to insure an adequate flow to the bearings without danger of overoiling them. The bearings 51 of the pump unit are adequately lubricated, the lower bearing by splash of oil and the upper bearing by creepage of oil along the connecting rod.

As in the case of my copending application Serial No. 389,839 filed October 11, 1929, oil previously cleansed by seepage through the filter 72, enters the open ports 60 of the small volume pump by gravity flow. There is always sufficient supply of oil above filter 72 to meet requirements for even a long run, and this supply is replenished while the vehicle is standing idle over night, and this by seepage through filter 72 from the volume standing in well 35. When filter 72 has become fouled, it is readily removed and replaced, substantially as in said copending application.

Means is preferably provided under the influence of pump P, to indicate automatically the suitability of the oil for further use, as a chassis and as an engine lubricant. This means comprises a suitable pressure gauge connecting across the ends of a flow resistance element maintained under the nearly constant temperature of the crank case or the water jacket, and through which element the pump discharges to the pressure line. The reading of the gauge is thus a measure of the viscosity of the oil.

In a specific embodiment, the flow resistance

is a unitary resistor element which comprises a cylindrical metal cartridge 91 having a pair of parallel longitudinal bores 92 and 93 therein, substantially filled by restriction pins 94 and 95. The upper ends of the bores 92 and 93 enter a common socket 96 in the top of the block 91, this socket being closed by a force fitted flanged cap 97 which affords leak-tight communication between the passages determined by the two restriction pins.

The inlet pin 94 is kept within the cartridge by perforated cap 98 press-fitted into a corresponding socket in the end of the cartridge. The bore 93 terminates at the slot 100 short of the end of the cartridge thus to confine the outlet pin 95, 15 the lower end 93' of which is stopped by the bottom of the slot.

The block 55 is provided with an upwardly extending segmental boss 101 having a socket 102 therein, in which the lower end of the resistor 20 cartridge 91 is received. The bottom of the socket 102 communicates through an opening 103 with the oil passage 69. In order to further guard against the entrance of foreign particles into the resistor, the opening 103 is provided with 25 a filter, substantially filling it, and consisting of a wool felt wad 104 arranged within a wire basket 105.

A segmental notch 100 formed in the side of cartridge 91 at the lower end of outlet bore 93 30 provides exit from the cartridge. Flow of oil through the resistor is into the socket 98, up through the bore 92, down through the bore 93 and out from the notch 100. Thus the two restriction pins and their associated bores define 35 series-connected flow resistance elements, so that when this resistor element is interposed in the path of flow of the output of pump P there will be a pressure drop across the ends of the resistor.

The pump P propelling the oil therethrough at nearly constant rate, the drop of pressure across the terminals of the resistor is proportional to the viscosity of the oil therethrough. The resistor being within the engine crank case 45 where more or less uniform temperature obtains during use in both summer and winter weather, any variation in the pressure drop across the resistor is proportional to and a measure of variation induced by a change in the 50 quality of the oil which is passing through the resistor.

Thus by merely connecting the two elements of a differential pressure gauge to opposite ends of the resistor a definite reading of oil quality 55 is obtained and it may be ascertained at a glance when the crank case oil has become so thinned or vitiated that it is inadvisable to use it further either for engine lubricating or chassis lubricating purposes. To indicate the quality of the 60 oil, a gauge G shown in Figs. 6 to 9 is preferably employed, the construction and connection of which will now be described.

The slot 100, at the outlet of the resistor cartridge communicates with a radial passageway 65 106 in the boss 101 into which is fitted the end of a small-bore conduit 107. Conduit 107 follows upwardly along the side of the cylinder 42 and communicates with an outlet socket 108 in the collar 44 into which conduit 17 is coupled.

Also communicating with the upper end of the conduit 107 is a second socket 109 into which is coupled a dead-end pipe 110 for the pressure gauge G. The conduit 70 leading from the end of the oil passageway 69 has its continuation 75

in a dead end pipe 111 leading to the gauge G, pipes 70 and 111 being united by suitable coupling 112 at the collar 44. The pressure potential in the pipe 111 is the same as that at the inlet of the resistor and the pressure potential in the pipe line 110 is the same as that at the outlet of the resistor.

Numerous expedients might be resorted to for operating an indicator or gauge from the differential pressure lines 110 and 111. In the present case is shown a sensitive gauge mechanism at the dashboard, of the type which includes a Bourdon tube 113, mounted within a casing 114. The tube is coupled to the pipe 111 and the pipe 110 directly connected into the interior of the gauge casing, so that the reading on the gauge corresponds to the pressure differential at opposite ends of the resistor element which, as previously noted, is a measure of the viscosity of the oil in the crank case. The means for connecting the needle or other indicator 115 to the tube may be entirely conventional and is not shown here.

The scale upon which this needle reads preferably, as best seen in Fig. 6, carries legends indicating good oil, thin oil, and empty although it may have a numerical scale of viscosity readings, if desired. Whenever there is no differential of pressure between the contents of the Bourdon tube and that of the gauge casing, the gauge will read empty, the pressure differential falling to zero during running of the vehicle, only on failure of oil supply to the pump or upon the pump itself becoming inoperative.

The resistor is employed in the present system merely as an adjunct to obtain the necessary pressure drop to produce the gauge reading which indicates the quality of the oil. Though the resistor is connected in series with the distributing chassis lines, it has no effect on oil distribution, the pump of constant feed rate, here shown propelling substantially at uniform rate despite the added frictional losses in the resistor. The resistor shown has the added virtue of impeding leak should a serious break occur in the chassis lines.

The expansive force of the air trapped in the gauge G and in the upper ends of tubes 110 and 111 helps to level out the pressure on the chassis lines between successive pump strokes, especially where a pump is used of larger effective volume and lesser frequency of operation than that specifically herein disclosed.

The modification of Figs. 10 to 13 inclusive, is shown mounted in the water jacket of the engine where nearly uniform high temperature conditions exist throughout the year. Since many of the elements of the two systems are duplicates, detailed showing of the inertia motor pump and mechanism has been avoided.

In this instance the only departure from conventional crank case structure is the formation of a laterally extending pocket 40^a in the crank case and the provision of a boss 116 projecting upwardly and outwardly from the sloping wall 117 of the crank case. A motor pump unit 118, generally similar to that previously described, is dropped through the circular sleeve defined by the boss 116. The collar 119 carried by the upper end of the unit 118 rests upon the top face of the boss and is secured by screws 120.

Here again, the inertia motor (not shown) operates the pump P', forcing oil into a conduit 121 which follows along the outer surface of the

unit 118 and terminates in a cross bore 122 in the collar 119.

From the cross bore 122, the oil is forced by the pump into a pipe 123 which terminates in a T fitting 124. This T fitting communicates through the pipe 125 with the stem of the pressure gauge G and through a short pipe 126 with the inlet 127 of the resistor element 128 screwed into a suitable opening 129 in the outer wall 130 of the engine water jacket 131. From the resistor outlet 132 the oil is led through a pipe 133 delivering through a second T fitting 134. From this fitting a pipe 135 leads to the casing of the gauge G and a pipe 136 delivers to the system of distributing conduits on the chassis. The oil in flowing from the pipe 126 into the pipe 133 passes through the serially arranged flow resistance elements of the resistor. The gauge again is so connected as to read pressure differential at opposite sides of the resistor. Pump discharge rate and resistor temperature remaining nearly constant, the gauge reading will always be indicative of the viscosity i. e., the quality of the oil in the crank case.

A desirable form of resistor 128 in this instance is shown in detail in Fig. 13. It consists of a body 137 having a cylindrical bore 138 therein, within which cartridge 139 is fitted, said cartridge being formed with a pair of longitudinal passageways 140 and 141 accommodating the restriction pins 142 and 143. The body includes a reduced threaded portion 144 to be screwed into the opening in the water jacket, portion 144 defining with the enlarged end of the body, a shoulder 145 which is adapted to press a gasket 146 against the outer face of the jacket and prevent leakage of water therefrom. Inwardly from the reduced portion 144 the body is further reduced at 147 and a cap 148 press-fitted over it clamps a disk 149 against the end of the body and serves to hold the restriction pins 142 and 143 against endwise displacement in one direction.

A retainer cup 150 force-fitted into a socket 151 in the outer end of the bore 141 holds pin 143 against movement in the other direction, while a strainer wad 152 within a wire mesh basket 153 is fitted into a radial socket 154 in the cartridge 139, said socket intersecting the outer end of the passage 140 and said strainer limiting outward movement of the restriction pin 142.

Diametrically opposed sockets 166 and 155 for oil inlet and outlet fittings are formed in the body 137. Socket 155 registers with the strainer 152 and at its inner end has a retainer cup 156 force-fitted therein and holding the strainer in place and serving also as an abutment for the coupling sleeve (not shown) of the compression bushing 132. The cartridge 139 is formed with a socket 157 communicating with the socket 151 and having an enlarged outer end 158 in which is mounted a filter wad 159, within a screen cage 160. This wad is protected by a cap 161 fitted over the projecting end of the block 139 and being struck inwardly at 162 for entry of lubricant. The cap 161 is itself completely enclosed by a flanged threaded cap 163 screwed onto the outer end of the resistor body 137, this cap together with the body 137 and the cap 161 providing an oil chamber 164 to which oil is admitted from inlet socket 166 by way of inclined passageway 165.

Oil admitted to chamber 164 flows through the openings in the cap 161, through the filter 159, and past the resistance element 143 into oil chamber 166, thence past the restriction pin 142, 75

through the strainer or filter 152 and out through exit socket 155 to the distributing system therebeyond.

The modified form of lubricating system shown 5 in Figs. 10 to 13 inclusive, functions on the principle of the system previously described. It operates to feed oil at substantially constant rate during all running conditions, to the chassis bearings and the condition of the oil being used is 10 always indicated by the gauge.

The flow resistance imposed by the resistor of Fig. 3 or that of Fig. 13, may be much higher, if desired, than that of the distributing system or of any one drip plug thereof, but it need be 15 no greater than necessary to produce the required pressure drop for gauge reading. The resistor of either of these embodiments may be readily applied, when of sufficiently high resistance, as the primary volume-feed control in a lubricating 20 system embodying a pump not of constant feed rate, as for example the engine oil pump.

The pump unit shown in Figs. 2 to 5 and 10 and the viscosity measuring units, shown in Figs. 3 to 5 and 6 to 13 may, of course, be used 25 in other connections than in combination with a chassis lubricating system, the viscosity measuring unit being broadly adapted to measuring the viscosity of lubricants or other fluids, and the pump unit being adapted to be associated with 30 machinery generally other than crank cases of automobiles.

I claim:

1. In combination with a motor vehicle, having a crank case lubricant reservoir, a lubricating installation for the chassis bearings, comprising a 35 source of oil supply including a pump and reservoir unit, in gravity lubricant communication with said crank case reservoir, an individual automatic motor for said pump actuated from the operating 40 vehicle for lubrication of said bearings, and distributing conduits leading from said pumps to said bearings and having flow controlling outlets associated with the chassis bearings.

2. In combination with a vehicle chassis of a 45 pair of independently operating motors thereon, one motor being self-lubricating and serving to propel the chassis, a chassis lubricating pump actuated by the other motor, and feeding lubricant to the chassis bearings, a crank case having 50 a common oil supply for the pump and the propelling motor, an oil distributing system into which oil is forced by the pump, said system having highly restricted outlets subject to clogging by minute foreign particles, means to cleanse the 55 oil for the propelling motor after it has lubricated such motor and means to filter the oil for the chassis lubricating system before it enters the pump thereof, said chassis lubricating pump being provided with an independent lubricant 60 reservoir in which it is immersed below the level of the lubricant, and a gravity feed from the crank case to said independent reservoir to cause said independent reservoir to be filled to above the level of said pump.

3. In an automotive vehicle, the combination 65 with a chassis and an engine thereon, of a chassis lubricating system including a chassis lubricating pump deriving lubricant from the crank case of the engine, a plurality of lubricant filled 70 distributing conduits into which lubricant is forced by the pump, outlets from the conduit system delivering to the chassis bearings, each outlet including means to impose an invariant, high flow 75 resistance to the emission of oil from the system and means for automatically operating said pump

throughout operation of the vehicle, said chassis lubricating pump being provided with an independent lubricant reservoir in which it is immersed below the level of the lubricant, and a gravity feed from the crank case to said independent reservoir to cause said independent reservoir to be filled to above the level of said pump. 5

4. In an automotive vehicle, the combination 10 with a chassis and an engine thereon, of a chassis lubricating system, including a chassis lubricating pump deriving lubricant from the crank case of the engine, a plurality of lubricant filled distributing conduits into which lubricant is forced by the pump, each conduit outlet having an invariant, high flow resistance to the emission 15 of oil from the system and a motor for operating the pump deriving energy from vehicle vibrations, said chassis lubricating pump being provided with an independent lubricant reservoir in which it is immersed below the level of the lubricant, and a gravity feed from the crank case to 20 said independent reservoir to cause said independent reservoir to be filled to above the level of said pump.

5. In an automotive vehicle, the combination 25 with a chassis and an engine with a crank case lubricant reservoir thereon, of a chassis lubricating system, including a chassis lubricating pump deriving lubricant from the crank case of the engine, a plurality of lubricant filled distributing 30 conduits into which lubricant is forced by the chassis pump, each conduit outlet having an invariant high flow resistance to the emission of oil from the system and a motor for operating said pump, said motor being housed within a 35 casing and being spaced from the operating engine parts, said chassis lubricating pump being provided with an independent lubricant reservoir fed by gravity from said crank case, said pump being provided with an inlet which is maintained 40 below the level of lubricant in said independent reservoir.

6. In an automotive vehicle, the combination 45 with a chassis and an engine thereon, of a chassis lubricating system including a plurality of 50 lubricant-filled distributing conduits having restricted outlets to the bearings to be lubricated, a pump in the crank case of the engine operative to continuously force a repeated series of small charges of crank case oil into the distributing system, while the vehicle is in motion, and means spaced from the operating engine parts and operated only upon movement of the vehicle over a 55 road for operating the pump, said chassis lubricating pump being provided with an independent lubricant reservoir fed by gravity from said crank case, said pump being provided with an inlet which is maintained below the level of lubricant in 60 said independent reservoir.

7. In an automotive vehicle, the combination 65 with the chassis and an engine thereon, of a chassis lubricating system including a plurality of lubricant-filled distributing conduits having restricted outlets to the bearings to be lubricated, a pump in the crank case of the engine operative 70 to continuously force a repeated series of small charges of crank case oil into the distributing system, while the vehicle is in motion, and means independent of the engine for operating the pump, comprising an inertia motor deriving energy from vehicle vibrations and directly connected to the pump.

8. In an automotive vehicle, the combination 75 with the chassis and a motor thereon, of a chassis lubricating system including a plurality of

- distributing conduits having restricted outlets to the bearings to be lubricated, a pump in the crank case of the engine operative to continuously force a repeated series of small charges of crank case oil into the distributing system while the vehicle is in motion, means independent of the motor for operating the pump, said means comprising an inertia motor deriving energy from vehicle vibrations and directly connected to the pump, the inertia motor and pump being housed within a common casing, and providing a unitary pump and motor structure bodily removable from the crank case.
9. The combination with a chassis frame and an engine thereon, of a pump and motor unit for a chassis lubricating system, said unit including a reciprocating inertia motor and a self-portioning plunger type force pump directly connected together, mounted in the crank case and receiving a supply of oil therefrom by gravity, a large area dense filter guarding the inlet to the pump and retarding gravity flow thereto and a reservoir chamber above the pump normally maintaining a standing supply of filtered oil in which the pump is immersed.
10. In a lubricating system of the character which includes liquid-filled distributing conduits having high resistance outlets and a force pump for continuously feeding small charges of lubricant into the system, means for indicating the viscosity of the oil including an invariant flow resistance element in the flow line and a differential pressure gauge connected to the flow line at opposite sides of such element.
11. In a chassis lubricating system of the character which includes liquid-filled distributing conduits having high resistance outlets and a means for substantially continuously feeding lubricant into the system at a substantially uniform rate, means for indicating the viscosity of the oil including an element of invariant high flow resistance in the flow line and a differential pressure gauge connected to the flow line at opposite sides of said element.
12. In a chassis lubricating system of the character which includes liquid-filled distributing conduits having high resistance outlets and a means for substantially continuously feeding lubricant into the system at a substantially uniform rate, means for indicating the viscosity of the oil including an element of invariant high flow resistance in the flow line and a differential pressure gauge connected to the flow line at opposite sides of said element, said element being disposed in a position where its temperature is maintained nearly uniform by the heat of the engine.
13. In a chassis lubricating system of the character which includes liquid-filled distributing conduits having high resistance outlets and a means for substantially continuously feeding lubricant into the system at a substantially uniform rate, means for indicating the viscosity of the oil including an element of invariant high flow resistance in the flow line and a differential pressure gauge connected to the flow line at opposite sides of said element, and means to maintain the temperature of the flow line substantially constant at the region of the resistance element.
14. In a chassis lubricating system of the character in which crank case oil is forced through distributing conduits to the chassis bearings, means to indicate the viscosity of the oil, said means comprising an element of invariant high flow resistances arranged in the flow line and in a position where its temperature is maintained nearly constant by the heat of the engine, and means to measure the pressure drop across the resistance element.
15. In a chassis lubricating system of the character in which crank case oil is forced through distributing conduits to the chassis bearings, means to indicate the viscosity of the oil, said means comprising an element of invariant high flow resistances arranged in the flow line and in a position where its temperature is maintained nearly constant by the heat of the engine and means to measure the pressure drop across the resistance element, said means comprising an indicator arranged to read said pressure drop in terms of oil quality.
16. In a chassis lubricating system of the character which includes liquid-filled distributing conduits having high resistance outlets and a means for substantially continuously feeding lubricant into the system at a substantially uniform rate, means for indicating the viscosity of the oil including an element of invariant high flow resistance in the flow line and a differential pressure gauge connected to the flow line at opposite sides of said element, said resistance element being arranged within the crank case.
17. In a chassis lubricating system of the character which includes liquid-filled distributing conduits having high resistance outlets and a means for substantially continuously feeding lubricant into the system at a substantially uniform rate, means for indicating the viscosity of the oil including an element of invariant high flow resistance in the flow line and a differential pressure gauge connected to the flow line at opposite sides of said element, said resistance element being arranged in the water jacket of the engine.
18. In a chassis lubricating system of the character which includes liquid-filled distributing conduits having high resistance outlets and a pump means for substantially continuously feeding lubricant into the system at a substantially uniform rate, means for indicating the viscosity of the oil including an element of invariant high flow resistance in the flow line and a differential pressure gauge connected to the flow line at opposite sides of said element, said resistance element being arranged within the crank case, and forming a unitary part of the pump means.
19. A centralized force feed lubricating system of the character which includes liquid-filled distributing conduits having invariant, high-resistance, flow controlling outlet fittings, means to continuously force repeated small charges of lubricant at a substantially constant rate into the system, and a gauge for indicating the viscosity of the oil which is being fed into the system.
20. A centralized force feed lubricating system which includes liquid-filled distributing conduits having invariant, high-resistance, flow controlling outlet fittings, means to substantially continuously feed lubricant into the system, a drip plug resistance positioned between said means and said system in the course of lubricant flow, a pressure differential being created between the inlet and the outlet of the drip plug resistance, and a differential gauge in communication with opposite ends of said drip plug resistance for indicating the viscosity of oil which is being fed into the system.
21. A centralized pressure lubricating apparatus which includes a system of liquid filled dis-

tributing conduits having flow outlets of invariant high resistance, a continuously operating pump of substantially uniform feed rate to force lubricant into the conduits, a flow resistance element in the main conduit supply line beyond the pump and a gauge to indicate the pressure differential of the oil between opposite sides of the resistance element.

22. In a lubricating apparatus, a liquid filled distributing conduit system having flow outlets of invariant high flow resistance, a conduit to convey liquid to the distributing conduits, a pump to continuously force liquid into said conveying conduit, and a viscosimeter including a resistor element arranged in said conveying conduit and a gauge registering the pressure differential between opposite sides of the resistor.

23. In a lubricating apparatus, a liquid filled distributing conduit system having flow outlets of invariant high flow resistance, a conduit to convey liquid to the distributing conduits, a pump to continuously force liquid at nearly constant feed rate into said conveying conduit, and a viscosimeter including a resistor element arranged in said conveying conduit, a gauge operating on pressure differential between opposite sides of the resistor, and said resistor being so disposed that its temperature is maintained substantially constant whereby changes in the pressure differential of the oil are indicative primarily of variations in the viscosity of the oil.

24. An internal combustion engine including a crank case, the lower portion of which is adapted to serve as a reservoir for crank case oil, a partition in the crank case segregating a well of oil from the main body of oil in the reservoir, said partition extending to substantially the high oil level, an opening in the partition and a filter covering said opening through which oil may flow by slow seepage to equalize levels in the reservoir and the well and a chassis lubricating pump in said well.

25. An internal combustion engine including a crank case, the lower portion of which is adapted to serve as a reservoir for crank case oil, a partition in the crank case segregating a well of oil from the main body of oil in the reservoir, an opening in the partition, a filter covering said opening through which oil may flow by slow seepage to equalize levels in the reservoir and the well, and an engine oil cleaner receiving oil from the reservoir and feeding it into the well.

26. An internal combustion engine including a crank case, the lower portion of which is adapted to serve as a reservoir for crank case oil, a partition in the crank case segregating a well of oil from the main body of oil in the reservoir, a filter in the partition permitting slow seepage of oil therethrough to equalize levels in the reservoir and the well, and said crank case having an opening therein above the well and through which a pump unit for a chassis lubricating system is adapted to be inserted.

27. The combination with an engine crank case of a unitary elongated motor and pump unit for a chassis lubricating system, said unit including an elongated housing member adapted to be inserted through an opening in the crank case and to depend into the oil in the latter, said housing member adjacent its upper end being encircled by a supporting collar adapted to lie against the outer surface of the crank case around said opening, said unit at its upper end consisting of a motor casing and a movable actuating member in said casing and at its lower end consisting of a

pump casing and a movable liquid actuating member in said pump casing, said unit also including rigid connecting means between said motor casing and said pump casing, and actuating connecting means between said movable actuating member and said liquid actuating member, said collar being connected to said motor casing, and said pump and motor casing being unconnected and out of contact with said crank case except through said collar.

28. The combination with an engine crank case of a unitary elongated motor and pump unit for a chassis lubricating system, said unit including an elongated housing member adapted to be inserted through an opening in the crank case to depend into the oil in the latter, said housing member adjacent its upper end being encircled by a supporting collar adapted to lie against the outer surface of the crank case around said opening, said crank case surface being shaped to provide a platform for the collar, and screws retaining the collar against the platform, said unit at its upper end consisting of a motor casing and a movable actuating member in said casing and at its lower end consisting of a pump casing and a movable liquid actuating member in said pump casing, said unit also including rigid connecting means between said motor casing and said pump casing, and actuating connecting means between said movable actuating member and said liquid actuating member, said collar being connected to said motor casing, and said pump and motor casing being unconnected and out of contact with said crank case except through said collar.

29. The combination with an engine crank case having an opening in its top of a unitary elongated pump and motor unit for a chassis lubricating system inserted through said opening and extending into the oil in the crank case, said unit including an elongated cylindrical housing and a collar fixed to the upper end of the housing and limiting the insertion of the unit into the crank case, said unit at its upper end consisting of a motor casing and a movable actuating member in said casing and at its lower end consisting of a pump casing and a movable liquid actuating member in said pump casing, said unit also including rigid connecting means between said motor casing and said pump casing, and actuating connecting means between said movable actuating member and said liquid actuating member, said collar being connected to said motor casing, and said pump and motor casing being unconnected and out of contact with said crank case except through said collar.

30. The combination with an engine crank case having an opening in its top, of a pump and motor unit for a chassis lubricating system inserted through said opening and extending into the oil in the crank case, said unit including an elongated housing, a collar fixed to the upper end of the housing and limiting the insertion of the unit into the crank case, said housing being of smaller diameter than the opening and an oil delivery pipe leading from along the surface of the housing from the pump into the collar.

31. The combination with an engine crank case having an opening in its top, of a pump and motor unit for a chassis lubricating system inserted through said opening and extending into the oil in the crank case, said unit including an elongated cylindrical housing, a collar fixed to the upper end of the housing and limiting the insertion of the unit into the crank case, said housing being of smaller diameter than the opening, an

oil delivery pipe leading from along the outer surface of the housing from the pump into the collar and said collar being constructed to receive an outlet pipe to the distributing system and to provide communication between said pipes.

32. A unitary elongated motor and pump unit for a force feed centralized chassis lubricating system and the like, said unit adapted to be bodily inserted into the crank case of an engine and including a collar adjacent its upper end to limit the extent of its insertion, said unit at its upper end consisting of a motor casing and a movable actuating member in said casing and at its lower end consisting of a pump casing and a movable liquid actuating member in said pump casing, said unit also including rigid connecting means between said motor casing and said pump casing, and actuating connecting means between said movable actuating member and said liquid actuating member, said collar being connected to said motor casing, and said pump and motor casing being unconnected and out of contact with said crank case except through said collar.

33. A motor and pump unit for chassis lubricating systems or the like, said unit including an elongated cylindrical casing, a reciprocating inertia motor in the upper end of the casing and a plunger type force pump in the lower end of the casing directly connected to the motor, a filter-guarded passage-way through which oil may flow by gravity to immerse the pump when the lower end of the casing is immersed in oil, and a collar about the upper end of the casing for coaction with suitable supporting means.

34. A motor and pump unit for chassis lubricating systems or the like, said unit including an elongated cylindrical casing, a reciprocating inertia motor in the upper end of the casing and a plunger type force pump in the lower end of the casing directly connected to the motor, a filter guarded passage-way through which oil may flow by gravity to immerse the pump when the lower end of the casing is immersed in oil, a collar about the upper end of the casing for coaction with suitable supporting means, said filter means comprising a unitary assemblage bodily removable through the lower end of the casing.

35. A motor and pump unit for chassis lubricating systems or the like, said unit including an elongated casing, a motor in the upper end of the casing and a force pump in the lower end of the casing operated by the motor, a filter guarded passage way through which oil may flow by gravity to immerse the pump when the lower end of the casing is immersed in oil, a collar about the upper end of the casing for coaction with suitable supporting means, and a pipe line leading along the exterior of the cylinder from the pump outlet to the collar, the collar being constructed to receive a discharge pipe and to provide connection between said pipes.

36. A motor and pump unit of the class described including an elongated cylindrical casing, a cylindrical reinforcing and liner sleeve at the intermediate portion of the casing, a pair of dished partition members force fitted into the ends of the sleeve and abutting the latter, closure members for the top and bottom of the casing cooperating with the partition members to define an upper motor chamber, a lower pump chamber and an intermediate reservoir chamber and a connecting rod for the motor and pump having slide bearings in said partitions.

37. A pump and filter unit adapted to be immersed in oil, said unit including a casing, a

partition block extending transversely thereof, a pump of the self-porting and unpacked plunger type arranged in said partition block, said block having an opening therein through which oil may flow by gravity above the partition to immerse and supply the pump, a filter assemblage guarding said passage, said filter assemblage comprising a cylindrical filter pad, a bottom plate upon which the pad is secured and means to removably retain the bottom plate in position within the casing with the filter pad clamped between said plate and the partition block and with the passage way disposed interiorly of the filter pad.

38. A pump and filter unit adapted to be immersed in oil, said unit including a casing, a partition block extending transversely thereof, a pump of the self-porting and unpacked plunger type, arranged in said partition block, said block having an opening therein through which oil may flow by gravity above the partition to immerse and supply the pump, a filter assemblage comprising a cylindrical filter pad, a bottom plate upon which the pad is secured and means to removably retain the bottom plate in position within the casing with the filter pad clamped between said plate and the partition block and with the passage way disposed interiorly of the filter pad, said block and said plate having oppositely facing retaining ribs thereon to exert a clamping pressure on the filter pad.

39. A motor and pump unit for chassis lubricating systems adapted to be mounted in the crank case of an engine and to derive oil therefrom, said unit including a cylindrical casing, an inertia motor in the upper end thereof and a minute capacity force pump of the self-porting plunger type mounted in the lower end thereof and directly connected to the power element of the motor, and a resistor element also arranged within the casing and in the path of oil flow from the outlet side of the pump, and adapted to serve as the control device of a viscosimeter.

40. A motor and pump unit for chassis lubricating systems adapted to be mounted in the crank case of an engine and to derive oil therefrom, said unit including a casing, a motor in the upper end thereof, a force pump mounted in the lower end thereof and connected to the motor, a resistor element adapted to serve as the control device of a viscosimeter, said element being arranged within the casing and in the path of oil flow from the outlet side of the pump, means to filter oil flowing to the pump and means to filter oil flowing to the resistor element after it has left the pump.

41. A motor and pump unit for chassis lubricating systems adapted to be mounted in an oil reservoir, said unit including a casing, a motor in the upper end thereof and a force pump in the lower end thereof and connected to the motor, a resistor element adapted to serve as the control device of a viscosimeter, said element being also arranged within the casing and in the path of oil flow from the outlet side of the pump, the pump including a supporting block element and the resistor comprising a cartridge fixed in the block.

42. A viscosimeter for fluid pressure systems including an element in the flow line of said systems which is highly resistant to flow and a differential pressure gauge to measure the pressure differential between the inlet to and the

outlet from said element including a liquid-tight casing, a Bourdon tube within the casing, an indicator actuated by movement of the tube, a dial plate with which the indicator is adapted to coact, and means for placing the interior of the tube and the interior of the casing respectively in communication with liquids, the pressure differential of which is to be measured, said systems including a relatively constant feed pump forcing lubricant through said flow line and also including means to maintain said element at a relatively constant temperature.

43. A viscosimeter for fluid pressure systems including an element in the flow line of said systems which is highly resistant to flow and a differential pressure gauge connected to said line at opposite sides of said element, said gauge including a casing and a Bourdon tube therein, the tube being in communication with the liquid in the line at one side of the resistance and the casing being in communication with the liquid in the line at the other side of the resistance, said systems including a relatively constant feed pump forcing lubricant through said flow line and also including means to maintain said element at a relatively constant temperature.

44. A viscosimeter for fluid pressure systems including a resistor element in the flow line of said system and a differential pressure gauge connected to said line at opposite sides of said element, said gauge including a casing and a Bourdon tube respectively connected to the liquid in the line at opposite sides of the resistance, means to maintain the resistor element at nearly constant temperature, a pointer actuated by movement of the tube and a scale associated with the pointer to indicate the quality of the liquid passing through the resistor, said systems including a relatively constant feed pump forcing lubricant through said flow line and also including means to maintain said element at a relatively constant temperature.

45. A chassis lubricating system of the character which includes a central reservoir, a continuously operating minute capacity force pump, an oil distributing conduit into which lubricant from the reservoir is forced by the pump, said conduit having outlets of invariant high flow resistance, a resistance element in the conduit also of high flow resistance and through which oil must pass on its way to the outlets, a differential pressure gauge connected to the conduit line at opposite ends of said resistance element and means to maintain the resistance element at a nearly constant temperature.

46. A centralized chassis lubricating system including a reservoir, a force pump deriving oil from the reservoir and feeding at nearly constant rate, a conduit line into which oil is continuously forced by the pump to its point of use, and a viscosimeter including a high flow resistance element in the conduit line and a pressure gauge connected to the line at opposite sides of said element, said resistance element being maintained at a nearly constant temperature whereby uniform pump operation and a uniform resistance to flow at the conduit outlets permits the viscosimeter to indicate the quality of the oil being pumped through the conduit.

70. 47. In a motor vehicle, the combination of an engine having an oil sump, an automatic pump of substantially constant feed rate for delivering oil from the sump to the chassis bearings, and means for indicating the viscosity of the oil in the sump, said means comprising a flow resistance

maintained under substantially the temperature of the engine structure and disposed in the course of oil flow from the pump to the chassis system and a differential pressure measuring gauge connected across the terminals of said resistance. 5

48. A central lubricating installation comprising a branched distribution system provided with a single inlet conduit, restricted outlets associated with said system, a substantially continuously discharging relatively minute reciprocating pump 10 at the inlet and an additional restriction positioned upon said inlet between said pump and ahead of the branching of the system.

49. A lubricant distributing installation comprising a branched conduit system with a single 15 inlet, a lubricant source of supply, a conduit establishing communication between said source of supply and said conduit system at said lubricant inlet, a multiplicity of bores containing restricting pins in series associated with said communicating conduit and a multiplicity of bores containing pins in parallel associated with the outlets of said branched conduit system, the first 20 of said series pins being movable in respect to its bore to pump lubricant and the remaining series 25 and the parallel pins being substantially fixed in position in respect to their bores.

50. In a central chassis lubricating installation, distributing piping system having highly restricted calibrated flow control fittings at the outlet 30 branches thereof, a force pump of minute capacity at the inlet to the system, a pressure-multiplying mechanical transmission converting a relatively low pressure impulse applied in the motion of the vehicle into a relatively high pressure 35 expelling stroke of the pump, and a restriction positioned between said pump and the inlet to said system having substantially higher restricting effect than said flow control fittings.

51. A chassis lubricating apparatus including a 40 lubricant-filled, pressure-tight distributing conduit system, highly restricted flow-controlling outlets at the points of lubricant delivery, a reservoir, a force pump of minute volume deriving its charge from the reservoir and feeding it into 45 the inlet of the distributing system, an inertia motor deriving energy from vehicle vibration and including an inertia weight as the power element, said weight being directly connected to the expelling element of the force pump whereby minute 50 charges of lubricant are forced into the system at rapidly succeeding intervals to maintain a substantially continuous and relative slow flow from the outlets during operation of the vehicle and a restriction positioned between said pump and the 55 inlet to said system having substantially higher restricting effect than said flow control fittings.

52. A chassis lubricating system of the character which includes a central reservoir, a lubricant force pump, an oil distributing conduit into which 60 lubricant from the reservoir is forced by the pump, said conduit having outlets of invariant high flow resistance, a resistance element in the conduit also of high flow resistance and through which oil must pass on its way to the outlets, 65 and a differential pressure device connected to the conduit line at opposite sides of said resistance element and actuated by the change in lubricant pressure thereacross.

53. In a lubricant flow system, a pump for sub- 70 stantially continuously feeding lubricant into the system at a substantially uniform rate, means for indicating the viscosity of the oil including an element of invariant high flow resistance in the flow line and a pressure gauge connected to the 75

flow line at said element, said element being disposed in a position where its temperature is maintained nearly uniform.

54. In a lubricant flow system, a means for substantially continuously feeding lubricant into the system at a substantially uniform rate, means indicating the viscosity of the oil including an element of invariant high flow resistance in the flow line and a differential pressure gauge connected to the flow line at opposite sides of said element, and means to maintain the temperature of the flow line substantially constant at the region of the resistance element.

55. In an automobile lubricant flow system, a means for substantially continuously feeding lubricant into the system at a substantially uniform rate, means for indicating the viscosity of the oil including an element of invariant high flow resistance in the flow line and a differential pressure gauge connected to the flow line at opposite sides of said element, said resistance element being arranged within the crank case.

56. In an automobile lubricant flow system, a means for substantially continuously feeding lubricant into the system at a substantially uniform rate, means for indicating the viscosity of

the oil including an element of invariant high flow resistance in the flow line and a differential pressure gauge connected to the flow line at opposite sides of said element, said resistance element being arranged in the water jacket of the engine. 5

57. A detachable pump and filter unit to be inserted into a lubricant pocket forming a part of the structure to be lubricated, having an opening in the top thereof to receive said unit, and adapted to be immersed in oil, said unit including an elongated supporting structure, a pump of the self-porting and unpacked plunger type, having a pump block at the lower end of the structure, said block having an opening therein through which oil may flow by gravity to supply 15 the pump, a filter assemblage guarding said passage, said filter assemblage comprising a filter pad, a plate upon which the pad is secured and means to removably retain the filter in position on said plate and an automatically driven reciprocating motor and a supporting collar at the upper end of said structure, said collar having screw connections to the upper edge of said pocket.

JOSEPH BIJUR. 25
